UNITED STATES PATENT OFFICE

154,225

DESIGN FOR A MIXING BOWL

Herbert H. Varney, Red Wing, Minn.

Application December 18, 1947, Serial No. 143,200

Term of patent 3½ years

(Cl. D44—10)

To all whom it may concern:

Be it known that I, Herbert H. Varney, a citizen of the United States of America, residing in Red Wing, county of Goodhue, and State of Minnesota, have invented a new, original, and ornamental Design for a Mixing Bowl, of which the following is a specification, reference being had to the accompanying drawing, forming part thereof, wherein the figure is a front perspective view of a mixing bowl showing my new design.

I claim:

The ornamental design for a mixing bowl, substantially as shown.

HERBERT H. VARNEY.
